UNITED STATES PATENT OFFICE.

CHARLES F. ERN, JR., OF NEW YORK, N. Y.

RAZOR.

1,107,662.

Specification of Letters Patent. Patented Aug. 18, 1914.

Application filed August 23, 1912. Serial No. 716,588.

To all whom it may concern:

Be it known that I, CHARLES F. ERN, Jr., a subject of the Emperor of Germany, residing at No. 610 West One Hundred and 5 Fifteenth street, New York, N. Y., have invented new and useful Improvements in Razors, of which the following is a specification.

This invention relates to razors.

10 One of the objects of the invention is to provide a handle for the razor which will effectively protect the cutting edge of the blade from being damaged when closed, while at the same time permitting the handle to be kept in a clean and sanitary condition.

Another object is to provide means for locking the blade in its closed position and preventing it from being accidentally 20 opened.

Another object is to provide a device of this character in which the blade is automatically guided to enter the handle centrally with respect to the side portions 25 thereof.

Other objects will in part be obvious and in part be pointed out hereinafter.

In the accompanying drawings showing an illustrative embodiment of this invention, 30 and in which the same reference numeral refers to similar parts in the several figures: Figure 1 is a side elevational view of the razor, the blade being shown in an open position. Fig. 2 is a top plan view, the blade 35 being shown opened and extending at approximately right angles with the handle. Fig. 3 is a sectional view, on an enlarged scale, taken on the line A—A, Fig. 2.

In the illustrative embodiment of the invention shown in the drawings, the handle of the razor is formed from a blank of sheet metal bent at its middle to form side portions 1 and 2, and a bottom portion 3. The edges of the blank are stamped or otherwise bent to form corrugations or ribs 4, which strengthen the handle, and at the same time provide a smooth surface for the edges of the side portions, whereby the razor may be handled without danger of injuring 45 the hand from rough metal edges. The bottom portion 3 forms a guard, as it prevents the introduction between the side portions of the handle of anything which might injure the cutting edge of the blade. In order 50 to hold the side portions 1 and 2 in position, the handle is provided at each end with a re-

movable fastening screw. At its outer end the fastening means comprises a screw 5 and a nut 6, of any suitable construction. At the other end the fastening means comprises a screw 7 and a nut 8, the latter of which is preferably formed elongated, as clearly shown in Fig. 1, whereby it may engage the ribs 4, and be prevented from turning thereby as the screw 7 is inserted or withdrawn. It is of course understood that the screw 7 passes through a suitable perforation in the shank 9 of the razor blade 10, thereby forming a pivot upon which the razor blade may be turned in the usual manner.

In order to facilitate the cleaning of the interior of the handle to render the same sanitary, the bottom portion 3 is provided with a plurality of perforations 11, which as shown, are preferably formed as slits extending transversely with respect to the handle, although, of course, perforations of any other shape may be provided without departing from the spirit of the invention. 70 When it is desired to clean the interior of the handle water may be run therethrough. If however, a more careful cleaning is deemed necessary, the screws 5 and 7 may be removed from the ends of the handle, thus 75 permitting the side portions 1 and 2 to spring apart, if the handle is made from resilient metal, or to be spread apart if the handle is made of non-resilient metal. When the side portions have assumed such 80 a position, a brush or other suitable cleaning implement may readily be inserted between them, and the entire inner surface of the handle may be thoroughly cleaned and dried. After cleaning, the side portions are 85 forced inward, and the screws 5 and 7 and their associated nuts 6 and 8 are again placed in position. It will also be understood that by means of the removable screw 7, a new blade may be substituted for the 90 old one whenever desired.

In order to prevent the accidental opening of the blade, the inwardly bent edges of the side portions are provided with extensions 12, 12, which are formed integral with the 105 handle and are flush with the edge thereof, thus being concealed and providing that there will be no upwardly extending portion which might interfere with the handling of the razor when using it. These extensions 12, which we positioned at the 110 portion of the handle which receives the shank

of the blade, serve to guide the blade to enter the handle centrally with respect to the side portions.

Assuming the blade to be in its open position, as it is closed, the shank 9 thereof will be engaged by the extensions 12 before the blade 10 enters the handle. The engaging of the extensions 12 by the shank will force the side portions 1 and 2 to separate slightly in view of the fact that the normal distance between the extensions 12 is less than the thickness of the shank 9. This not only forms a wider opening for the blade to pass in but will also tend to center the blade with respect to the handle. The position assumed by the side portions as the shank engages the extensions 12, is shown in dotted lines in Fig. 3. As the shank enters the handle, the side portions, which have been separated, as explained above, will resume their normal positions, in which the extensions 12 overlap the upper surface of the shank 9, as shown in full lines in Fig. 3, thereby effectually locking the blade within the handle, and preventing the accidental opening thereof. When it is desired to use the razor, a slight downward pressure on the outwardly extending portion 13 of the blade will be sufficient to cause the blade to open. While, of course, the handle may be formed of any suitable metal, I prefer to form it of a resilient metal in order that upon removal of the screws 5 and 7, the said

portions 1 and 2 will automatically spring apart to afford access to the interior of the handle for cleaning purposes.

Having described this invention in connection with the illustrative embodiment thereof, to the details of which disclosure the invention is not, of course, to be limited, what I claim as new and what is desired to be secured by Letters Patent is set forth in the appended claim:

In a razor, in combination, a blade and a handle therefor comprising side portions, each side portion being provided with an inwardly extending locking member flush with the front edge of said side portion for locking the blade in its closed position, said locking members being positioned at the portion of the handle which receives the shank of the blade whereby as the razor is closed said members will engage the shank of the blade before the blade enters the handle and thereby guide the blade to enter the handle centrally with respect to the sides thereof, each of said locking members being relatively immovable with respect to its associated side portion.

In testimony whereof I have signed my name to this specification in the presence of two subscribing witnesses.

CHARLES F. ERN, JR.
